UNITED STATES PATENT OFFICE.

WILLIAM N. WEST, OF KANSAS CITY, KANSAS, ASSIGNOR OF ONE-HALF TO LOUIS HECTOR, OF KANSAS CITY, MISSOURI.

TRAIN-DELIVERING AND STATION-RECEIVING MAIL-BAG APPARATUS.

No. 892,786.

Specification of Letters Patent.

Patented July 7, 1908.

Application filed November 25, 1907. Serial No. 403,656.

To all whom it may concern:

Be it known that I, WILLIAM N. WEST, a citizen of the United States, residing at Kansas City, in the county of Wyandotte and State of Kansas, have invented certain new and useful Improvements in Train-Delivering and Station-Receiving Mail-Bag Apparatus, of which the following is a specification.

This invention relates to train-delivering and station-receiving mail bag apparatus, and my object is to produce an apparatus which will operate efficiently and reliably with the minimum of wear and tear on the bags.

A further object is to produce a receiving apparatus which disposes the bags in a position out of the path of trains passing on the adjacent track and near the ground so as to facilitate its removal by the station agent or other person in charge.

A still further object is to produce a catcher capable of receiving and reliably holding one or a number of bags.

A still further object is to produce a buffer which offers an increased resistance to the throw imparted to the catcher by the bag or bags.

A still further object is to produce an apparatus of the character named, of comparatively simple, strong, durable and inexpensive construction.

With these general objects in view and others as hereinafter appear the invention consists in certain novel and peculiar features of construction and organization as hereinafter described and claimed; and in order that it may be fully understood reference is to be had to the accompanying drawings, in which—

Figure 1, is a top view of apparatus embodying my invention together with a part of a car equipped with the delivery part of the apparatus. Fig. 2, is a vertical section on line II—II of Fig. 1. Fig. 3, is a view of the receiving apparatus from the side most remote from the trackway. Fig. 4, is a vertical section of a part of the telescopic catcher-carrying standard. Fig. 5, is a section on line V—V of Fig. 4. Fig. 6, is a central vertical section of a part of the catcher. Fig. 7, is an enlarged view partly in elevation and partly in section of the upper part of the construction shown in Fig. 6. Fig. 8, is a section on the line VIII—VIII of Fig. 7.

In the said drawings 1 indicates a suitable

platform adjacent to a track-way 2 upon which travel cars 3, the car shown being a mail car. 4 indicates brackets secured to said car at suitable points and 5 a vertical shaft journaled in said brackets and provided with arms 6 at its upper and lower ends, said arms being equipped at their outer ends with pins 7 arranged horizontally, projecting rearward with respect to the direction of travel of the car.

8 are rings or loops engaging the pins 7 and connected by straps or other flexible connections 9 to the upper and lower ends of a mail bag 10 so as to support the latter in a vertical position, and in order to swing the mail bag from a point within the car to a point exterior thereof as indicated in the drawings, the shaft 5 is equipped with a handle 11, any suitable ratchet or equivalent mechanism, not shown, being employed to secure the delivery frame as the parts 5, 6, 7 and 11 inclusive, are hereinafter termed, in the required position.

12 indicates a pair of bearings secured to platform 1, and 13 a rock shaft journaled in said bearings and arranged transversely of the track-way and provided with a pair of collars 14 to guard against endwise movement. Pivoted at 15 to shaft 13 to swing transversely of the track-way is a catcher-carrying telescopic standard, the lower or pivot member 16 of said standard being tubular, and 17 indicates a pair of buffers in the shape of coiled springs mounted on rock shaft 13 and secured at one end as at 18 to the platform and having their opposite ends 19 terminating in hooks 20, exerting pressure in opposite directions upon member 16 of the pivoted standard the said spring buffers acting in opposition to each other in order to maintain said member in substantially a vertical position when not overcome by a preponderating pressure. 21 is a slot formed by and between a pair of arches 22 which together constitute a rigid slotted 100 guide frame mounted upon the platform and inclining upward and inwardly toward the track-way for the purpose of compelling the telescopic standard when rocking shaft 13 in either direction, to move outward and for 105 reversing such movement when returning to its upright position. 23 indicates pivoted catches mounted on one of the arches of the slotted frame and bridging the slot thereof, said catches being linked together pivotally 110

by bars 24 and held yieldingly bridging such slot by springs 25. 26 indicates the other member of the telescopic standard, said member 26 being angular in cross-section—5 preferably rectangular as shown in Fig. 5, and extending slidingly through the screw cap 27 upon the upper end of tubular member 16. At its lower end member 26 is equipped with a head 28 within the tubular member, a coiled spring 29 being mounted upon member 26 and bearing at its opposite ends against the cap 27 and head 28 for the purpose of holding the telescopic standard yieldingly contracted with its upper end in 10 a horizontal plane midway between arms 6 of the delivery apparatus. At its upper end the member 26 terminates in a substantially horizontal arm 30 which projects inward toward the track-way and in turn terminates 15 in a vertically arranged tubular hub 31 equipped with a set screw 32 for impingement upon a shaft 33 journaled in said tubular hub, said screw being adapted to clamp said shaft rigidly in position. At its upper 20 and lower ends which project beyond the corresponding ends of the tubular head, the shaft is provided with a pair of segmental slots 34 and 35 at opposite sides of its axis and journaled upon such slotted ends are the 25 ends of a pair of substantially U-shaped frames 36 and 37 which together constitute the frame work of a mail bag catcher, the member 36 being equipped with stud-bolts 38 projecting into slots 34 and member 37 30 with similar stud-bolt 39 projecting into slots 35, it being noted by reference to Fig. 1 particularly, that the two members of the 35 catcher conjointly form a U-shaped frame when viewed in plan and that the outer or free ends of the members of said catcher 40 are connected to the inner portions of the companion members by chains or equivalent flexible connections 40, the arrangement being such that said flexible connections occupy 45 intersecting planes so that when the mail bag is forced into the catcher disposed to receive it, as shown in Fig. 1, it shall come in contact with said chains and by pressure thereagainst cause the two members of the catcher to 50 swing inwardly as indicated by the adjacent arrows Fig. 1, so as to clasp the mail bag firmly between them, the flexible connections of course yielding under such pressure so as to eventually practically encircle the 55 mail bag, the distance which they clasp the latter being determined by its circumferential area, it being obvious that if two or three bags are fastened together for simultaneous delivery they will in a similar manner be 60 clasped between the chains and the frame members of the catcher.

To prevent the catcher opening and the consequent escape of the bag or bags caught therein, one member is provided with a ratchet toothed rack bar 41 and the other

with a spring-actuated pawl 42, the arrangement being such that the pawl, under the closing action of the catcher shall successively engage the teeth of the rack bar and thus guard against any accidental re-opening movement of the catcher, as will be readily understood by reference to Figs. 7 and 8.

To prevent the catcher swiveling bodily so as to accidentally face in the wrong direction to receive the mail bag from a passing train, the slots 34 and 35 and stud-bolts 38 and 39 are provided. By reference to Fig. 8 it will be seen that the frames 36 and 37 are free to swing in the direction indicated by 80 the contiguous arrows, and that either of them has a limited movement in the direction indicated by its adjacent arrow. It will also be noticed, however, that the stud-bolt 38 carried by frame 36 normally engages one 85 end wall of slot 34 and consequently will prevent swinging movement of said member 36 in the opposite direction to that indicated by its respective arrow and that stud-bolt 39 by engagement with one end wall of slot 90 35 will likewise prevent opposite swinging movement of member 37, this arrangement therefore preventing what I term swivel movement bodily of the catcher, it being further noticed that the pawl and rack bar 95 action will also prevent any accidental pivotal movement of said members in the direction in which they are permitted to swing so that there is practically no danger of accidental collapse or closing movement of the 100 catcher.

In the event that the catcher is to be disposed in the direction to receive a mail bag from a train moving in the opposite direction to that indicated in Fig. 1, the set screw 32 105 is loosened so that the operator by grasping the catcher may turn its shaft 33 half way around, the set screw being then screwed home to secure it in its new position.

Now as a mail bag strikes against the 110 crossed chains or flexible connections 40 and overcoming the resistance of the spring-actuated pawl effects the closing movement of the catcher, its impact causes the latter, together with the telescopic standard supporting it and the shaft 13, to swing or rock in the direction the train is moving, the opposing spring-buffer hereinbefore described, yielding to permit such action to occur, it being understood in this connection that as 115 such action begins the supporting pins 7 are withdrawn by the passing train from the rings or loops of the mail bag so as to leave the latter wholly supported by the catcher. The swinging or rocking movement above 120 referred to will be proportioned to the speed of the train and the weight of the bag, the strength of the spring-buffer being such that it will yield sufficiently for the lightest bag delivered by the slowest train to move the 130

telescopic standard beyond the first catch 23, such catch immediately resuming its original position to prevent the restoration of the standard and the bag to its original position under the action of such buffer. 5 With a train moving fast the standard may turn sufficiently far to pass the second catch or even the last catch. It will be seen that the swing or rocking movement of the standard is not only opposed by a spring-buffer but by the frictional engagement with the arches and particularly the inner arch of the slotted frame, and to still further counteract and diminish the movement imparted 10 to such telescopic standard by the impact of the bag on the catcher I have made the said standard telescopic so that as it swings downward in either direction the impetus of the bag at its upper end will tend to slide 15 member 26 outward in member 16, the spring 29 offering yielding resistance to such action.

It will be seen from the above description, taken in connection with the drawings, that 25 I have produced means for receiving a mail bag from a moving train with a minimum of wear and tear on the bag, and means for swinging and securing the bag away from dangerous proximity to the train and where 30 it can be conveniently removed from the catcher, it being understood that when it is desired to restore the latter to operative position to receive another bag, the rod 24 is manipulated to withdraw the catch or 35 catches 23 from the path of the telescopic standard so as to permit the compressed buffer to restore the standard to vertical position, it being noted in this connection that the buffer which tends to push the standard 40 in the same direction traversed by the train, performs no function.

I wish it to be understood that I reserve the right to make changes that practically fall within the spirit and scope of the appended claims.

Having thus described the invention what I claim as new and desire to secure by Letters Patent, is:—

1. In an apparatus of the character described, a suitable guide frame, a standard secured at its lower end to rock longitudinally of said frame, means for yieldingly holding it in an upright position, a mail-bag catcher carried at the upper end of said standard above said guide frame, and a spring-actuated catch carried by the guide frame and adapted to yield to rocking movement of the standard and to prevent the latter from automatically returning to its upright position in the event that it passes said catch in its rocking movement.

2. In an apparatus of the character described, a suitable guide frame, a standard secured at its lower end to rock longitudinally of said frame, means for yieldingly

holding it in an upright position, a reversible mail bag catcher carried at the upper end of the standard, and spring-actuated catches carried by the guide frame at opposite sides of and in the path of rocking movement of the standard, for the purpose set forth. 70

3. In an apparatus of the character described, a suitably supported guide frame, a spring-actuated catch carried thereby, a rock shaft extending transversely of said frame, a catcher-carrying standard engaging the guide frame and secured at its lower end to the rock shaft, and means for yieldingly resisting rocking movement of said standard. 75

4. In an apparatus of the character described, an inclined guide frame, a substantially upright standard engaging the guide frame and arranged at its lower end to rock in the direction of the length of the frame and to operate pivotally transversely of said frame, yielding means for holding said standard in a substantially vertical position, a mail bag catcher carried at the upper end of the standard, and a pivoted catch carried by the frame in the path of rocking movement 80 of the standard, for the purpose set forth. 90

5. In an apparatus of the character described, a longitudinally slotted and laterally inclined arched guide frame, a standard projecting up through the slot of said guide frame and arranged to rock in the slot thereof and to also operate pivotally transversely of the guide frame, yielding means for holding the standard in a substantially upright position, a mail bag catcher carried by the standard above the guide frame at the side toward which the latter leans, and a spring-actuated catch carried by the guide frame and bridging the slot thereof, for the purpose set forth. 105

6. In an apparatus of the character described, a longitudinally slotted and laterally inclined arched guide frame, a standard projecting up through the slot of said guide frame and arranged to rock in the slot thereof and to also operate pivotally transversely of the guide frame, yielding means for holding the standard in a substantially upright position, a reversible mail bag catcher carried by the standard above the guide frame at the side toward which the latter leans, and a series of spring-actuated catches carried by the guide frame and bridging the longitudinal slot thereof in the path of rocking movement of the standard in each direction. 110 115

7. In an apparatus of the character described, a longitudinally slotted and laterally inclined arched guide frame, a standard projecting up through the slot of said guide frame and arranged to rock in the slot thereof and to also operate pivotally transversely of the guide frame, yielding means for holding the standard in a substantially upright position, a reversible mail bag catcher carried by the standard above the guide frame at the side 120 125 130

toward which the latter leans, a series of 5
spring-actuated catches carried by the guide
frame and bridging the longitudinal slot
thereof in the path of rocking movement of
the standard in each direction, and a link
pivotally connecting the catches of each series
together.

8. In an apparatus of the character de-
scribed, an extensible standard arranged to
10 rock in either direction and consisting of two
members fitted slidably together, yielding
means for holding the standard in a sub-
stantially vertical or upright position, and a
mail bag catcher carried by the standard.

15 9. In an apparatus of the character de-
scribed, a suitable guide frame, a shaft ar-
ranged transversely thereof, a standard com-
prising a tubular member secured to rock
with the shaft and engaging the guide frame,
20 a member fitting telescopically within the
tubular member and projecting upwardly
therefrom, and a spring engaging the mem-
bers to hold the standard yieldingly con-
tracted, a mail bag catcher carried by the
25 upper member of the standard, and a spring-
actuated catch carried by the guide frame
in the path of the rocking movement of the
lower member of the standard, for the pur-
pose set forth.

30 10. In an apparatus of the character de-
scribed, a suitable standard secured at its
lower end to rock and provided at its upper
end with a hub portion, a shaft secured in
said hub portion, a mail bag catcher carried
35 by said shaft and comprising two members
pivoted to said shaft and adapted to swing
inward or toward each other, and crossed
flexible connections connecting each member
near its outer end with the other member
40 near its inner end.

11. In an apparatus of the character de-
scribed, a suitable standard secured at its
lower end to rock and provided at its upper
end with a hub portion, a shaft secured in
said hub portion, a mail bag catcher carried
45 by said shaft and comprising two members
pivoted to said shaft and adapted to swing
inward or toward each other, crossed flexible
connections connecting each member near its
outer end with the other member near its
50 inner end, and means for yieldingly resisting
movement of the members of the catches
together.

12. In an apparatus of the character de-
scribed, the combination of a pivoted frame 55
carried by a car, and embodying arms pro-
jecting outwardly and equipped at their
outer ends with pins projecting rearwardly
with respect to the direction of travel of the
car, a mail bag arranged vertically between 60
and provided with loops or rings engaging
said pins, a frame suitably secured at one
side of the path of the car, a shaft suitably
journaled and extending transversely of the
travel of the car, a standard engaging the 65
frame and carried by said shaft, means for
yieldingly holding the standard upright, and
a mail bag catcher carried at the upper end
of the standard in a position to intercept the
70 mail bag and consisting of a pair of pivoted
members, crossed flexible connections con-
necting each member near its outer end with
the other member near its inner end and
adapted when struck by the mail bag to
cause said members to close and clasp the 75
mail bag between them, and means for
automatically preventing said members from
opening after the mail bag is clasped between
them.

13. In an apparatus of the character de- 80
scribed, the combination of a shaft provided
at opposite sides with slots, and a catcher
consisting of two members pivoted upon said
shaft and provided at the opposite side of
the latter to that from which they project 85
with stud-bolts projecting into said slots and
when the catcher is fully opened bearing
against end walls of said slots.

14. The combination of a standard pro-
vided with a vertical hub, a shaft therein, 90
means to clamp the shaft against rotatable
action, a catcher secured upon said shaft
above and below said hub, and consisting of
a pair of substantially-U-shaped members
connected by crossed flexible chains, means 95
for yieldingly resisting closing movement of
said members, and means for preventing
opposite movement of said members beyond
a predetermined point.

In testimony whereof I affix my signature, 100
in the presence of two witnesses.

WILLIAM N. WEST.
